United States Patent Office

Des. 221,753

Patented Sept. 7, 1971

221,753

FIRE HYDRANT

John J. Smith, Decatur, Ill., assignor to
Mueller Co., Decatur, Ill.

Filed July 8, 1970, Ser. No. 23,856

Term of patent 14 years

Int. Cl. D23—01

U.S. Cl. D23—12

Fig. 2.
Fig. 3.

Fig. 1.
Fig. 4.

FIG. 1 is a perspective view taken from the top and front of a fire hydrant embodying my new design;

FIG. 2 is a perspective view taken from the top and left side thereof;

FIG. 3 is a perspective view taken from the top and right side thereof; and

FIG. 4 is a top plan view thereof.

I claim:

The ornamental design for a fire hydrant, as shown and described.
